UNITED STATES PATENT OFFICE.

LOUIS V. ARONSON, OF NEWARK, NEW JERSEY.

PYROPHOROUS LIGHTER.

1,084,386.

Specification of Letters Patent. Patented Jan. 13, 1914.

Application filed April 25, 1913. Serial No. 763,492.

To all whom it may concern:

Be it known that I, LOUIS V. ARONSON, a citizen of the United States, and a resident of Newark, in the county of Essex and State of New Jersey, have invented certain new and useful Improvements in Pyrophorous Lighters, of which the following is a specification.

The invention relates to pyrophorous lighters, viz.—lighters in which a spark is produced in proximity to a suitable fuel by rubbing or scratching with a metal striker a spark producing material such as cerium-iron or the like.

It relates more particularly to lighters in which the fuel is contained in the lighter casing or in the striker itself and in which the material employed as fuel is a solidified hydrocarbon or the like such as solidified gasolene, petroleum, etc.

The invention has for its object to simplify the construction and operation of such apparatus, and to provide a positive feed of the fuel material to the striker.

The nature of the invention will be best understood when described in connection with the accompanying drawings, in which—

Figure 1 is an elevation of the improved lighter. Fig. 2 is a vertical section thereof. Fig. 3 is a vertical section illustrating a fuel containing striker. Fig. 4 is a vertical section of a modified form of the lighter. Fig. 5 is a plan thereof. Fig. 6 is a part transverse section, on an enlarged scale, taken on the line 6—6, Fig. 4.

Similar characters of reference designate corresponding parts throughout the several views.

Referring to the drawings, 10 designates a hollow fuel container for the solidified fuel and carries preferably at its bottom or side a strip of the pyrophorous material 11 against which the suitably sharpened end 12 of a striker 13 is adapted to rub or scratch to cause sparks for the ignition of the fuel, as is well understood. The container consists of an outer shell 14 and an inner shell 15 snugly fitting therein and providing a closed container, the two shells being secured against accidental separation by providing a slight indentation 16 in the inner shell and an inward projection 17 adapted

to snap therein on the outer shell. When it is desired to fill the container with the fuel, the two shells may be readily separated by exerting a slight force to draw them apart.

Centrally disposed within the container and extending longitudinally thereof to near the bottom of the same is a tubular member 18 provided with an external thread 19 and secured to the top of the inner shell 15 but rotatable with respect thereto. Mounted to turn about this tubular member is a washer or plunger 20 threaded internally to fit the threads 19 of the tubular member 18 and non-circular or of such a shape with respect to the inner shell 15 that it can not rotate with respect thereto but may only reciprocate therein as the member 18 is turned accordingly. To turn this member 18 within which is adapted to fit the striker 13 closing the upper end thereof, it is necessary merely to force the striker member therein sufficiently to insure a snug fit, the end thereof being made conical for this purpose, and then turn the striker. To further insure the turning of the same, slots 21 may be provided in the end of the tubular member projecting beyond the casing and into which corresponding pins 22 extending outwardly from the striker may be inserted. As the striker is thus turned, and with it the said tubular member, plate 20 is advanced and forces the solidified fuel toward the bottom of the casing where it accumulates upon the inner end 12 of the striker which is preferably made in the form of a hard metal scoop or the like with a sharp striking edge. Above this scoop 12, the striker may be provided, furthermore, with a series of horizontal grooves 23 to retain the fuel.

In using the improved lighter, the striker, whose end has thus gathered a sufficient portion of the solidified fuel from the container, is withdrawn and the said friction end 12 thereof scratched or rubbed along the strip of pyrophorous material 11 to produce the sparks for igniting the fuel. When not in use, the striker is returned within the member 18 and pressed sufficiently therein to obtain a tight closure thereof. In thus employing a solidified fuel instead of the usual dangerous liquid fuels, not only is the danger in the use of these lighters greatly less-

sened, but the recharging of the fuel will be less frequently required. In fact, where the former style with ordinary use requires recharging at short intervals, the present form 5 would not require recharging for long periods.

In Fig. 3, I have shown the striker itself as containing the fuel. For this purpose, the striker consists of an outer casing 30 10 providing a fuel container and surrounding a centrally disposed threaded rod, or as herein illustrated merely two twisted wires 31 terminating beyond the casing in a knurled head 32. A removable plug 33 surrounds this rod and is locked to the casing as by means of pins and slots; and, moreover, seals the one end of the said casing. The other end of the casing is closed except for a ring of perforations 34 and a central 20 annular opening 35 about a hard metal striking member 36, provided with a sharp striking edge. A washer or plunger 37 fits about the threaded rod 31; and the said washer is threaded internally and of such a shape 25 with respect to the inner wall of the casing that it cannot rotate with respect thereto but only reciprocates within the shell as the rod 31 is turned accordingly in turning the head 32. The fuel is thereby forced out 30 through the perforations 34 and annular openings 35 in the desired quantity and ignited when the striker end 36 is rubbed along or scratched upon the pyrophorous material.

35 In Figs. 4, 5 and 6 I have disclosed a modified form of the lighter shown in Figs. 1 and 2, the inner shell 15 being replaced by a short friction top or cap 51 secured to the tubular member 18 which is rotatable relatively thereto, but in one direction only. The rotation is effected by means of a washer 52 with milled edge, said washer being located above the top of the cover 51 and projecting slightly beyond its edge so 40 that the same may be conveniently grasped. To prevent the member 18 from being too readily turned and to control the feed motion of the plunger 20, ratchet teeth 53 have been provided at the upper portion of the 45 member 18 within the cap 51, said teeth being adapted to be engaged by a pawl member 54, preferably as a tongue cut from the wall of the said cap or lid 51. The striker member is shown as fitting the outer end of 50 the tubular member 18 merely by friction as the turning of said member is not in this embodiment necessarily effected by the turning of the striker, but preferably by the milled washer 52.

55 With the hereinbefore described constructions, the fuel is fed as required; and particularly with the constructions illustrated in Figs. 4 to 6, the feed may be adjusted with great nicety.

I claim:—

1. In an ignition apparatus of the character described, the combination with a suitable container adapted to retain solidified fuel; of a striker member; and means to feed the solidified fuel to the striker member. 70

2. In an ignition apparatus of the character described, the combination with a suitable container adapted to retain solidified fuel; of a striker member having a hard rubbing surface and adapted to remove and retain a portion of the said fuel from the said container; and means to feed the fuel to said striker member. 75

3. In an ignition apparatus of the character described, the combination with a suitable container adapted to retain solidified fuel; of a striker member to receive the fuel; a rotatable member within said container; and a washer fitted about and engaging the 80 rotatable member and adapted to be advanced, when the same is turned, to feed the fuel to the striker member. 85

4. In an ignition apparatus of the character described, the combination with a suitable container adapted to retain solidified fuel and a rotatable tubular member within said container; of a striker member adapted to fit within said tubular member; and a washer fitted about and engaging the same 90 to feed the fuel to the striker member. 95

5. In an ignition apparatus of the character described, the combination with a suitable container adapted to retain solidified fuel; a cap therefor; an externally threaded 100 tubular member carried by said cap and rotatable with respect thereto; of a striker member adapted to fit within said tubular member; and a threaded washer fitted about and engaging the same to feed the fuel to 105 the striker member.

6. In an ignition apparatus of the character described, the combination with a suitable container adapted to retain solidified fuel; a cap therefor; an externally threaded 110 tubular member carried by said cap and rotatable with respect thereto; of a striker member adapted to fit within said tubular member; a threaded washer fitted about and engaging the same to feed the fuel to the 115 striker member; ratchet teeth provided on said tubular member; and a pawl extending from said cover adapted to engage said ratchet teeth.

7. In an ignition apparatus of the character described, the combination with a suitable container adapted to retain solidified fuel; a cap therefor; an externally threaded tubular member carried by said cap and rotatable with respect thereto; of a striker member adapted to fit within said tubular member; a washer outside of the cap and movable with said tubular member to rotate 120

125

the same; and a threaded washer fitted about and engaging said tubular member to feed the fuel to the striker member.

8. In an ignition apparatus of the character described; a suitable container to retain solidified fuel; and a striker member provided with a series of horizontal peripheral grooves to receive the solidified fuel.

Signed at Newark, in the county of Essex, and State of New Jersey, this 23rd day of 10 April, A. D. 1913.

LOUIS V. ARONSON.
